FIG. 1.

Inventor
PAULINE WINNER BANTA,
By *[Signature]* Nathan Dickerson
attorney.

UNITED STATES PATENT OFFICE.

PAULINE WIMER BANTA, OF TAMPA, FLORIDA.

HEATING-STOVE.

1,336,412.

Specification of Letters Patent. Patented Apr. 13, 1920.

Application filed November 24, 1919. Serial No. 340,263.

To all whom it may concern:

Be it known that I, PAULINE WIMER BANTA, a citizen of the United States, residing at Tampa, in the county of Hillsborough, 5 State of Florida, have invented certain new and useful Improvements in Heating-Stoves; and I do declare the following to be a full, clear, and exact description of the invention, such as will enable others skilled in 10 the art to which it pertains to make and use same.

My invention relates to an improvement in heating stoves and more particularly to a stove wherein the heat is generated by 15 means of a lamp.

It consists of the several features and in 20 the construction, combination and arrangement of features as more fully hereafter described and claimed.

The object of the invention is to provide 25 a stove which will confine, compress and direct the heat in such a manner that its volume and heating capacity will be increased to a maximum degree.

A further object is to provide a stove in 30 which the heat generated thereby is used to the best advantage with very little if any waste.

A further object is to provide a stove 35 which is simple, inexpensive and durable in construction, exceedingly easy to use and attractive in appearance.

Referring to the drawings:—

Figure 1 is a perspective view of my in- 40 vention.

Fig. 2 is a horizontal section on the line $x-x$ of Fig. 1.

In the drawings in which like reference 45 characters denote like parts 1 represents the stove the body portion 2 of which comprises a central vertical tube 3 which is surrounded by a series of vertical tubes 4, preferably 6, but of course the number may be increased or diminished to suit the conditions of use.

These tubes 4 are seated on a lower air 50 chamber 5, one half of each lower end being closed as at 6 by the top of the chamber 5 and the other half open as at 7 to the atmosphere or outer air and the chamber 5 being provided with suitable supporting legs 8, with an opening 9 in the bottom for the reception of the chimney of a suitable lamp 10 by which heat is to be generated, and a central opening 11 which registers and furnishes communication with the central tube

3. An upper closed air chamber 12, preferably about one half the size of the lower air chamber, is provided with which the central tube 3 and the tubes 4 communicate.

The object in having the upper air chamber smaller than the lower air chamber is to cause the compression and increase the volume of heat which is generated in the lower air chamber and this compression or pressure forces the increased volume of heat 60 down and out of the series of tubes 4.

In use the lamp or other heat generating device is lighted and the air in the lower air chamber is heated and forced up the central air tube 3 into the upper air chamber 12 70 where it is compressed, and the pressure caused by such compression forces the heated air down the series of tubes 4 and out at the bottom, thereof, into the room or other place desired to be heated.

I do not wish to be understood as limiting myself to the specific details of construction and arrangement as herein described and illustrated, as it is manifest that variations and modifications may be made in the 80 features of construction and arrangement, in the adaption of the device to various conditions of use, without departing from the spirit and scope of my invention and improvements. I therefore reserve the right to 85 all such variations and modifications as properly fall within the scope of my invention and the terms of the following claims.

What I claim is:—

1. In a heating stove, an upper air chamber, a lower air chamber, a central tube communicating with both of said air chambers and a series of tubes communicating with the said upper and lower air chambers, said tubes mounted on the lower air chamber and 95 having a portion of their lower ends closed by said chamber and the remaining portion being open to the atmosphere.

2. In a heating stove, an upper air chamber, a lower air chamber, a central tube communicating with both of said air chambers and a series of tubes surrounding the said central tube and connecting and communicating with said upper and lower air chambers, said tubes situated above the lower air 105 chamber and having a portion of their lower ends closed and the remaining portion being open to the atmosphere.

3. In a heating stove, an upper air chamber, a lower air chamber, a central tube com- 110

- communicating with both of said air chambers and a series of tubes surrounding the central tube and communicating with the said air chambers, said tubes mounted on the lower air chamber and extending laterally beyond the same and having a portion of their lower ends closed by the said lower air chamber and the remaining portion being open to the atmosphere.
- 10 4. In a heating stove, a lower air chamber, an upper air chamber of less height than the lower air chamber, a central tube communicating with both of said air chambers and a series of tubes surrounding the central tube and communicating with the said air chambers, said tubes extending lat-

erally beyond the lower air chamber and having a portion of their lower ends closed and the remaining portion open to the atmosphere.

20

5. In a heating stove, an upper air chamber, a lower air chamber, a central tube communicating with both of said air chambers and a series of tubes communicating with the said upper and lower air chambers, said tubes having a portion of their lower ends closed and the remaining portion open to the atmosphere.

25 In testimony whereof I have affixed my signature.

PAULINE WIMER BANTA.
